HAROLD O. PETERSON, OF RIVERHEAD, NEW YORK, ASSIGNOR TO RADIO CORPORATION OF AMERICA, A CORPORATION OF DELAWARE

TUNING MEANS

Application filed March 27, 1929. Serial No. 350,149.

This invention relates to tuning means, and more particularly to a tuning condenser for use in short wave radio equipment.

When constructing apparatus for use with very short waves, factors which ordinarily are negligible, such as the stray capacitance between a circuit and ground, become very appreciable, and must be accounted for in advance. The difficulties are overcome to a considerable extent by employing symmetrical circuits, such as pushpull electron emission tube circuits. However, at the extreme frequencies here considered, I have found that the balance of such circuits may be upset by the difference in the magnitude of the stray capacitance of the two sides of a tuning condenser with respect to ground. Furthermore, during tuning, or movement of the condenser rotor, the amount of this unbalance continually varies, thus complicating the problem.

To overcome this difficulty it has been suggested to use two equal condensers connected in series. This, however, halves the total amount of tuning capacitance and at the same time doubles the total amount of stray capacitance, thereby quadrupling the ratio of stray capacitance to tuning capacitance, whereas this ratio should be a minimum, especially when leading with exceedingly high frequencies, in order to prevent high losses.

The object of my invention is to provide a tuning reactance the stray capacitance of which is balanced or symmetrical, and which remains so even during movement of the rotor, but which at the same time is small in magnitude relative to the magnitude of the tuning capacitance. This object I fulfill by providing a tuning reactance consisting, structurally, of two similar stationary portions, two similar movable portions cooperating therewith, means for simultaneously and equally moving the movable portions, and means connecting each of the stationary portions with that movable portion which cooperates with the other stationary portion. The condensers are thus connected in parallel, so that the ratio of stray capacitance to tuning capacitance is not increased. At the same time, each terminal of the condenser being

connected to both a stationary portion and a movable portion, the stray capacitances between each terminal and ground remain equal.

In a preferred modification I provide a shielding compartment, and a tuning condenser for the resonant circuit of a push-pull electron emission tube stage comprising, structurally, two similar condensers arranged symmetrically with respect to the walls of the compartment and mechanically connected for unicontrol. The rotors are electrically insulated, and each of the rotors is connected with the stator of the other condenser, so that each side of the condenser consists of a rotor and a stator, in which case the stray capacitance between the tuning condenser and the shield obviously is symmetrical even during movement of the condenser rotors.

My invention is described more in detail in the following specification, which is accompanied by a drawing in which Figure 1 is a wiring diagram explanatory of my invention; Figure 2 is a schematic representation of one form of condenser; and Figure 3 illustrates a preferred modification.

Referring to Figure 1, there are a pair of electron emission tubes 42 and 44, to which a resonant circuit 46 is symmetrically coupled. In this case the circuit 46 is an input circuit connected to the control electrodes of the tubes. The circuit is arranged symmetrically, and therefore the mid point of the input and output inductances may be grounded with respect to radio frequency, preferably through blocking condensers, as shown, in order not to short circuit the potential sources for biasing the control electrodes and polarizing the anodes of the tubes.

The symmetry of the circuit is designed with a view to providing equal stray capacitance from each side of the circuit to ground. This stray capacitance has been represented by the condensers 50 and 52. It will be understood without difficulty that with the usual type of tuning condenser this symmetry will be upset, owing to the inequality of the stray capacitances of the stator and of the rotor of the tuning condenser. This inequality will cause a difference in the potentials on the control electrodes of the tubes, so that the

100

effective mid point of the circuit is varied, which upsets the desired symmetry. The difference cannot be compensated by the use of a fixed balancing condenser because the 5 amount of inequality varies as the rotor of the condenser is moved. The dissymmetry may be avoided by using two equal condensers connected in series, but this solution is not desirable because it quadruples the ratio of the 10 stray capacitance to the tuning capacitance, and in this field of work it is very important to keep the stray capacitance at a minimum.

Referring now to Figure 2 it will be seen that the tuning condenser consists, structurally, of two tuning condensers, 2 and 2'. There are two similar stationary portions 4 and 6, and two similar movable portions 8 and 10, cooperating with the stationary portions. The movable portions 8 and 10 are arranged 20 for unicontrol, by being on a common shaft, or by connection through a link 12. Although the movable portions 8 and 10 are connected mechanically, they are not connected electrically, being insulated by the insulator 12. 25 Instead, each movable portion is connected to the stationary portion cooperating with the other movable portion, that is, the movable portion 8 is connected to the stationary portion 6 and the movable portion 10 is connected to the stationary portion 4. Connections to the condenser are made by the leads 14 and 16. It is obvious that the condensers are connected in parallel, but that each side of the condenser consists of a stationary portion and a movable portion, instead of two stationary portions, or two movable portions. In this way material of the same mass and distribution is connected to each lead, and therefore the stray capacitances between each 40 side of the condenser and its general surroundings, or ground, are made equal.

The condensers, preferably, consist of interleaving plates of conventional form. Such a modification is illustrated in Figure 3, in 45 which the tuning condenser consists, structurally, of the two similar tuning condensers 20 and 22, each comprising a stator 24 and 26, and a rotor 28 and 30. The rotors are arranged mechanically for unicontrol, through 50 a tuning dial 32, but the rotors are electrically insulated by an insulator 34. As before, each rotor is connected to the other stator, as shown, and the entire condenser is connected in circuit by the leads 36 and 38. The condenser is surrounded by a shielding compartment 40, and the condensers 20 and 22 are symmetrically located with respect to the walls of this compartment.

It should be understood that the resonant 60 circuit shown in Figure 3 might be an output circuit, or other symmetrical circuit, as well as an input circuit.

I claim:

1. A tuning reactance comprising two similar stationary portions, two similar movable

portions cooperating therewith, means for simultaneously and equally moving the movable portions, and means for electrically cross connecting the various portions so that the stray capacitance between the terminals of 70 the tuning reactance and its surroundings is balanced, while its total magnitude, relative to the magnitude of the tuning reactance, is not increased.

2. A single tuning condenser comprising, 75 structurally, two similar condensers arranged for uni-control, and means for electrically cross connecting the stators and rotors of the condensers so that the stray capacitance between the tuning condenser and its surroundings is symmetrical during movement of the rotor, while the ratio of the stray capacitance to the tuning capacitance is not increased.

3. A tuning reactance comprising two similar stationary portions, two similar movable 80 portions cooperating therewith, means for simultaneously and equally moving the movable portions, means to electrically insulate the movable portions, and means connecting each of the stationary portions with that movable portion which cooperates with the other stationary portion, in order to balance 85 the stray capacitance between the terminals of the tuning reactance and its surroundings.

4. A single tuning condenser comprising, 90 structurally, two similar condensers arranged for uni-control, means to electrically insulate the rotors from one another, and means connecting the rotor of each condenser with the stator of the other condenser, in order to make 95 the stray capacitance between the tuning condenser and its surroundings symmetrical during movement of the rotors.

5. In combination, a shielding compartment and a tuning condenser, said tuning condenser comprising, structurally, two similar condensers arranged for uni-control and located symmetrically with respect to the walls of the compartment, means to electrically insulate the rotors of the condensers, and means to electrically connect the rotor of each condenser with the stator of the other condenser, so as to make the capacitance between the tuning condenser and the shield symmetrical 100 during movement of the condenser rotors.

6. In combination, a pushpull electron emission tube stage comprising two electron emission tubes and a resonant circuit symmetrically coupled therebetween, a shielding compartment, and a tuning condenser for the resonant circuit comprising, structurally, two similar condensers arranged symmetrically with respect to the walls of the compartment and mechanically connected for uni-control, means to electrically insulate the rotors, and means to electrically connect each of the rotors with the stator of the other condenser, in order to make the stray capacitance 115 between the tuning condenser and the shield 120

symmetrical during movement of the condenser rotors.

7. A tuning reactance comprising two similar stationary portions, two similar movable portions cooperating therewith, means for simultaneously and equally moving the movable portions, and connections of low impedance for cross connecting the movable and stationary portions.
- 10 8. A tuning condenser comprising, structurally, two similar condensers arranged for uni-control, and connections of low impedance cross connecting the rotors and stators of the two condensers.
- 15 9. A tuning reactance comprising two similar stationary portions, two similar movable portions cooperating therewith, means for simultaneously and equally moving the movable portions, means to electrically insulate the movable portions, and means connecting each of the stationary portions with that movable portion which cooperates with the other stationary portion.
- 20 10. A tuning condenser comprising, structurally, two similar condensers arranged for uniccontrol, means to electrically insulate the rotors from one another and means connecting the rotor of each condenser with the stator of the other condenser.
- 25 11. In combination, a pair of condensers, each condenser having a stator and a rotor, a low impedance connection from the stator of one condenser to the rotor of the other condenser and a low impedance connection from the rotor of the other condenser to the stator of the one condenser.
